(57) **CLAIM**

The ornamental design for a soccer bracelet, as shown and described.

DESCRIPTION

FIG. 1 is a perspective view of a soccer bracelet showing our new design;

FIG. 2 is a top plan view thereof;

FIG. 3 is a bottom plan view thereof;

FIG. 4 is a right side elevation view, the left side being a mirror image thereof;

FIG. 5 is a left end elevation view thereof; and,

FIG. 6 is a right end elevation view thereof.

The portion of the article shown in broken lines in FIGS. 1-6 is for illustrative purposes only and forms no part of the claimed design.
